UNITED STATES PATENT OFFICE.

WALTER SIEGERIST, OF ST. LOUIS, MISSOURI, ASSIGNOR TO HEINE BOILER COMPANY,
OF ST. LOUIS, MISSOURI, A CORPORATION OF MISSOURI.

STEAM BOILER.

Application filed August 4, 1923. Serial No. 655,671.

This invention relates to steam boilers of the type that comprise water-tubes, inclined slightly to the horizontal, and upright baffles arranged transversely of said tubes in such a way as to cause the gases to flow cross-wise of the tubes, in traveling from the combustion chamber of the boiler to the gas outlet.

The object of my invention is to provide an exceptionally efficient boiler of the general type referred to that has a relatively large combustion chamber which is not obstructed by the flue through which the gases escape from the boiler, and a tortuous passageway through which the gases flow transversely of the tubes numerous times in escaping from the combustion chamber.

The figure of the drawings is a vertical sectional view of a water tube boiler constructed in accordance with my invention.

Referring to the drawings, A and A' designate two banks of water tubes arranged in superimposed relation and inclined upwardly slightly with respect to the front wall 25 of the boiler, B designates a combustion chamber arranged below said tubes and C designates a flue through which the gases escape from the boiler. The gas outlet flue C is arranged at the rear end of the boiler, 30 preferably with its inlet end positioned in alignment with the space between two tube banks, and baffles are provided for causing the gases to make four transverse passes across the tubes of the upper bank, in traveling from the combustion chamber B to the gas outlet flue C, thereby producing a long, tortuous passageway for the gases in which the heat of the gases will be effectively absorbed by the boiler tubes. In 35 the form of my invention herein illustrated a front baffle 1 is arranged transversely of the tubes of the upper bank in opposed relation to the front wall of the boiler setting and disposed at such an angle to same as to produce a first up-pass that is contracted at 40 its upper end, a rear baffle 2 is arranged transversely of the tubes of the upper bank in opposed relation to the rear wall of the boiler setting and disposed at such an angle to same as to produce a final down-pass that 45 is contracted at its lower end, and a center baffle 3 is arranged transversely of the boiler at a point substantially midway the front and rear baffles so as to produce two intermediate passes, said middle baffle 3 extend-

ing downwardly from the top wall 4 of the boiler setting and terminating in the upper bank at a point above the lower side of said upper bank. A combustion chamber B extends rearwardly towards the rear end of the boiler and a transversely-disposed baffle 5 that extends parallel or substantially so to the boiler tubes is arranged between the tube banks in such a way that it will cause the gases which rise upwardly at the rear end of the combustion chamber to flow forwardly, longitudinally of the tubes of the lower bank and then upwardly through the first up-pass formed by the front wall of the boiler and by the front baffle 1. After reaching the upper end of the first up-pass the gases flow downwardly and rearwardly through the second pass formed by the front baffle 1 and the middle baffle 3, then upwardly and rearwardly through the third 70 pass formed by the middle baffle 3 and the rear baffle 2, and thence downwardly and rearwardly through the fourth pass to the gas outlet flue C at the rear end of the boiler which communicates with the lower end of the fourth pass. The baffle 5, which, for convenience, I will refer to as an upwardly inclined, horizontal baffle in distinction to the upright cross-baffles 1, 2 and 3 that extend transversely of the tubes of the upper bank, is provided at its rear end with a downwardly-inclined portion 6 so as to not obstruct the inlet end of the gas outlet flue C, and said baffle 5 is provided at its front end with an upwardly-inclined portion 7 that connects the baffle 5 with the front cross baffle 1 and which is disposed at such an angle that the gases which contact with the underside of the baffle 5 will hug the upwardly-inclined portion 7, in making the upward turn into the first up-pass, thereby preventing a gas pocket from being created in the first up-pass that retards the upward flow of the gases.

Due to the fact that the gas outlet flue C is arranged at the rear end of the boiler and leads from the space between the upper and lower tube banks, it is possible to make the combustion chamber B of the boiler very large. In fact, in the boiler herein illustrated the upper portion of the combustion chamber increases in height from the front to the rear of the boiler, and it extends substantially the entire depth and width of the boiler, thereby causing the tubes of the lower

bank A' to be subjected to radiant heat throughout their entire length. In addition to having an exceptionally large combustion chamber, my improved boiler is provided with a tortuous gas passageway which is of sufficient length to insure the gases being effectively cooled, in traveling from the combustion chamber to the gas outlet, said gas passageway being formed by three transversely-disposed baffles in the upper tube bank that cause the gases to flow across the tubes of the upper bank four times, or to make four passes, before reaching the gas outlet at the rear of the boiler.

If desired, a superheater D, of any preferred type, can be arranged in the space between the tube banks directly beneath the upwardly-inclined, horizontal baffle 5, this being a particularly desirable location for a superheater, because the elements of same are arranged in the direct path of travel of the gases that flow over the underside of the baffle 5, in traveling forwardly from the rear end of the combustion chamber to the first upward pass. The portion of the top side of the baffle 5 that is arranged between the upright cross baffles 1 and 2 in the upper bank acts as the floor of a dust hopper, and one of the side walls of said dust hopper is provided with a door 8 that can be opened when it becomes necessary to remove the dust, soot and the like that has accumulated on the top side of the baffle 5.

Having thus described my invention, what I claim as new and desire to secure by Letters Patent is:

1. A steam boiler, comprising superimposed banks of water tubes that project rearwardly and upwardly from the front wall of the boiler setting, a combustion chamber whose upper portion extends substantially the full length of the boiler so as to cause the tubes of the bottom bank to be subjected to radiant heat throughout substantially their entire length, a gas outlet at the rear

end of the boiler leading from the space between said banks, a transversely-disposed baffle in the space between said tube banks disposed substantially parallel to same and arranged over the rear end portion of the combustion chamber, and a plurality of transverse upright baffles in the upper tube bank disposed in such relation to each other and to the front and rear walls of the boiler setting as to form a first up-pass contracted at its upper end, a final down-pass contracted at its lower end, and a plurality of intermediate passes.

2. A steam boiler, comprising superimposed banks of water tubes that project rearwardly and upwardly from the front wall of the boiler setting, a combustion chamber whose upper portion extends substantially the full length of the boiler so as to cause the tubes of the lower bank to be subjected to radiant heat throughout substantially their entire length, a gas outlet at the rear end of the boiler leading from the space between said banks, a transversely-disposed baffle in the space between said tube banks disposed substantially parallel to same and arranged over the rear end portion of the combustion chamber, a front baffle in the upper bank arranged transversely of same and disposed at such an angle to the front wall of the boiler setting as to form a first up-pass contracted at its upper end, an inclined baffle portion connecting the lower end of said first baffle with the baffle between the tube banks, a rear baffle in the upper bank arranged transversely of same and disposed at such an angle to the rear wall of the boiler setting as to form a final down-pass contracted in its lower end, and an intermediate baffle projecting downwardly from the top of the boiler setting into said upper bank and terminating at a point above the lower side of said upper bank.

WALTER SIEGERIST.
